VENTILATING APPARATUS

Leo J. Riconda, City Island, N. Y., assignor to The Safety Car Heating & Lighting Company, a corporation of New Jersey

Application July 30, 1938, Serial No. 222,189

7 Claims. (Cl. 98—13)

This invention relates to ventilating apparatus, and more particularly to the construction of the air inlet on a railroad car or the like.

One of the objects of this invention is to provide a simple, inexpensive, and practical ventilating apparatus, well adapted to meet the varying conditions of use. Another object is to provide apparatus of the above character neat and attractive in appearance but sturdy in construction to withstand hard usage. A still further object is to provide apparatus of the above character which will be inexpensive to manufacture and easily assembled. Another object is to provide apparatus of the above character to move air into an air inlet in an efficient manner. Other objects will be in part obvious and in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which is shown one of the various possible embodiments of my invention:

Figure 1 is a perspective view of my ventilating apparatus installed on the roof of a railroad car;

Figure 2 is an enlarged vertical section taken along the line 2—2 of Figure 3;

Figure 3 is a front elevation of the apparatus having certain parts thereof broken away;

Figure 4 is a sectional elevation taken along the line 4—4 of Figure 2; and

Figures 5 and 6 are diagrammatic views indicating the operating characteristics of the apparatus.

As conducive to a clearer understanding of the various novel features of the invention, it might here be pointed out that the air inlet shown is a ventilating apparatus on a railroad car, particularly cars equipped with air conditioning equipment, and the inlet is located on the roof in an outer surface extending in the direction of car movement and with the inlet exposed to the full force of the air stream when the car is moving. In the past difficulty has been experienced with air intake apparatus due to the fact that the air stream builds up a low pressure area around the leading edge of the opening. This low pressure area cuts down considerably the amount of air introduced into the car. More specifically, referring to Figure 5, the action of an air stream on many ventilators now in use and lacking the deflectors disclosed herein, is

diagrammatically shown. Assuming that the car to which the ventilator is attached is moving from left to right, the left-hand wall 81 is at the trailing edge of the inlet opening and the right-hand wall 79 is at the leading edge of the inlet opening. With the ventilator thus positioned, the plane of the inlet opening extends in the direction of car movement, and the air stream passes the ventilator in the direction shown by the arrow and strikes the leading edge of the housing, flows thereunder and thence up in behind end wall 79. The action of the lower edge of the end wall on the air stream, plus the effect of the air stream passing under the ventilator, causes eddy currents to be set up behind this wall, as shown by the lines 80. These eddy currents suck the air in this portion of the ventilator downwardly and thus create a low pressure area therein. This prevents the ventilator from operating in an efficient manner. Furthermore, when the air stream strikes end wall 81 this wall has the same effect upon the air stream as wall 79 and a second set of eddy currents are set up therebehind, as indicated by lines 82. These eddy currents suck air from the inside of the ventilator under the lower edge of wall 81 and thus form another low pressure area within the ventilator. One of the various objects of this invention is to provide practical and efficient apparatus for overcoming the above-mentioned difficulties.

Referring now to Figure 1 of the drawings, a ventilator generally indicated at 10 is shown attached to a clerestory 11 of a railroad car covering the air intake opening therein. The ventilator includes a housing having a top 12, ends 13 and 14 (see also Figure 3), and a pair of doors 15 and 16 hinged to the front thereof. The bottom of the ventilator is provided with two openings 8 and 9 (Figure 4), which are covered by a pair of filters 56 and 57, respectively. Mounted below these openings upon the ends of the ventilators are two deflectors 17 and 18. These deflectors direct the air in an even stream into openings 8 and 9 in a manner which will be fully pointed out below.

Referring now to Figures 1 and 3, top 12 and ends 13 and 14 are preferably welded together and have flanges 19, 23 and 24 formed along their respective inner edges extending outwardly therefrom. These flanges have a series of holes 20 formed therein through which bolts may be passed to secure the housing to the clerestory.

As shown best in Figures 2 and 4, a supporting member 27 extends between and is secured to 55

- the lower rear edges of ends 13 and 14. This member has a flange 28 (Figure 2) extending upwardly along its rear edge and preferably has a series of holes, one of which is shown at 29, 5 formed therein adaptable to receive bolts which secure this flange to the clerestory of the car. A flange 30 extends downwardly from the forward edge of supporting member 27 for purposes to be more fully described hereinafter.
- 10 Extending between the lower edges of ends 13 and 14 and secured thereto at its outer ends is a supporting strip 31 (Figures 2 and 3). Extending along the under surface and secured adjacent the outer edge of top 12 is a depending portion 36 which has a projecting flange 37 formed thereon. Extending between projecting flange 37 and strip 31 is a channel-shaped member generally indicated at 39 (see Figures 2 and 3), the walls 40 and 41 of which extend outwardly to 20 ward the front of the housing. The forward edges of ends 13 and 14, walls 40 and 41, and flange 37 preferably lie in the same plane. The portions of flange 37 and strip 31 which would otherwise lie between walls 40 and 41 of channel 25 39 are cut away to permit door flanges to enter the channel, as will be described. The top of channel 39 is notched to interfit with flange 37. Thus channel flange 41, strip 31, flange 37, and the forward edge of end wall 14 frame the opening which receives filter 57 and provide a flanged aperture well adapted to receive door or closure 16, as will be more fully described hereinafter. Similarly channel flange 41, strip 31, flange 37, and the forward edge of end wall 13 frame a 35 flanged aperture or opening for door 15.
- Doors 15 and 16 are mounted on hinges 15a and 16a, respectively, and cover the apertures in the front of the housing. These doors have a flange extending inwardly from their edges (Figure 2) and register with the flanges of the apertures just described to effect therewith a reasonably tight seal against the admission of air to render the filters more efficient. Gaskets, one of which is shown in section at 48, (Figure 2) are 40 secured to the inner surface of the door and engage the aperture flanges when the doors are closed to further perfect the seal between the doors and their apertures.
- Depending from strip 31 (Figures 1 and 3) is 50 a series of lugs 35a, 35b, 35c, 35d, 35e, and 35f. The outer surfaces of these lugs lie in a plane rearwardly spaced from the forward edge of strip 31 (Figure 2) and the end of lugs 35a and 35f are preferably larger than lugs 35b, 35c, 35d, and 35e.
- Door 15 carries straps 61 which register respectively with lugs 35a, 35b, and 35c. Similarly, door 16 carries strap 62 adapted to register with lugs 35d, 35e, and 35f. Each of straps 61 and 62 60 has extending therethrough a screw 63 rotatably secured to the strap by a collar 64 (Figure 2) and a wing nut 49 attached to the screw on opposite sides of the strap. Each of lugs 35a, 35b, 35c, 35d, 35e, and 35f has a nut suitably attached 65 thereto in register with a hole in the lug through which screw 63 may be threaded into nut 65 when door 16 is closed. Thus the doors may be tightly sealed against their apertures by tightening their respective wing nuts.
- 70 At the center of the housing and extending between supporting strip 31 (Figure 2) and supporting member 27, is a supporting plate 38 (Figure 4). A channel 42 is secured to this plate and extends from the rear surface of channel 39 to 75 flange 28. The width of channel 42 is less than

the width of plate 38, leaving supporting edges 43 and 44 at its sides. A partition member 45 extends between the center portion of channel 42 and top 12 for purposes to be more fully described hereinafter.

5 Referring now to Figure 4, a pair of flanges 25 and 26 extend inwardly from the lower edges of end walls 13 and 14. These flanges are secured to the rear edge of supporting strip 31 and to the front edge of supporting member 27. Thus the openings 8 and 9 in the bottom of the housing are bounded by rim structures which are formed by strip 31, supporting member 27, edges 43 and 44, and flanges 25 and 26. These rims or frames around openings 8 and 9 serve as supports for a 10 pair of filters 56 and 57. Filters 56 and 57 are inserted through doors 15 and 16 and are held in proper alignment with respect to openings 8 and 9 by a series of lugs 58 which are secured to supporting member 27 (Figure 2) and by a pair of spacers 71 (see also Figure 1) attached to the 15 inner surfaces of doors 15 and 16.

20 In order to prevent vertical movement of the filters when they are in position in the housing, longitudinal springs 51, 52, 53 and 54 (Figures 2 and 4) are provided. These are secured to the inner surfaces of end walls 13 and 14 and on opposite sides of partition 45; they are preferably held in position by bolts which pass through loops formed on the ends of the springs and are all substantially similar in construction and installation to spring 53 (best shown in Figure 2) which is held in position by bolts 54a and 55 threaded into suitable nuts secured to partition 45. Springs 51 and 52 cooperate respectively 25 with flanges 25 and supporting edge 43 to hold filter 57 in place. Similarly springs 53 and 54 contact with supporting edge 44 and flange 26 to hold filter 56 in place. Thus filters 56 and 57 may be easily replaced through doors 15 and 16 and when 30 in position the longitudinal springs hold them in contact with the frames around openings 8 and 9 to prevent leakage of moisture and foreign material around their lower edges. Also the springs resiliently hold the filters against vibration.

35 As noted above, deflectors 17 and 18 (Figure 1) are positioned at opposite ends of the ventilator adjacent the lower edges of ends 13 and 14 (see also Figures 3 and 4). Deflector 17 extends between and is secured to lug 35a and flange 30, 40 while deflector 18 extends between and is secured to lug 35f and flange 30. The deflectors are preferably streamlined or tear-shaped in cross section (Figure 4), and when the car is moving in the direction of the arrow in Figure 4, deflector 45 17 is streamlined in the direction of car movement and presents a curved leading blunt edge 75 to the air stream which is then passing the ventilator in the opposite direction. This curved leading blunt edge tapers to a trailing edge 76 50 which streamlines the body of the deflector causing it to act upon the air stream in a way to be pointed out more fully hereinafter.

55 Deflector 17 adjacent end 13 is similar in construction and operation to deflector 18, and when 60 the car is moving opposite to the arrow in Figure 4 it presents a curved leading blunt edge 77 which tapers to a trailing edge 78. The deflectors are both slanted upwardly, as may be seen in Figures 3 and 4, so that the top surfaces 64 and 65 slant toward openings 8 and 9. In addition to this, the deflectors slant longitudinally from the plane of the inlet in the manner best shown in Figure 2.

65 Referring now to Figure 6, the operation of a 75

ventilator using a pair of deflectors of the type disclosed hereinabove is diagrammatically shown. In this figure the air stream passes the ventilator in the direction shown by the arrow and first strikes the curved leading edge 75 of deflector 18. Because of the streamlined surface the deflector presents to the air stream, the air stream follows the body of the deflector to its trailing edge and does not swing upwardly to create eddy currents behind end wall 83. Furthermore, the slanting surface 65 of the deflector directs the air stream up into the ventilator, as shown by line 84. Thus deflector 18 prevents the formation of eddy currents behind the leading edge 15 or behind wall 83 of the ventilator. This eliminates low pressure areas, directs the air stream into the ventilator, and smooths the air stream passing therethrough. By slanting the deflectors longitudinally (see also Figure 2), the air is delivered to the inlet in an even stream, and at the same time, the deflectors are reliably supported.

When the air stream referred to above strikes deflector 17 it divides, and some of the air stream 25 shoots directly into the ventilator, as is shown by lines 86. The rest of the air stream flows around the body of the deflector and thence rearwardly thereof. Thus this deflector prevents the air from being sucked under the trailing wall 30 of the ventilator and prevents the formation of a low pressure area in the rear section thereof.

When the car is moved in the opposite direction, the action of the deflectors upon the air stream is reversed, and thus the same result is produced regardless of the direction in which the car is moving. With the filters positioned horizontally, and the air moving upwardly therethrough, the filters are protected from the elements, and large pieces of dirt which might tend 40 to remain upon the surface of the filters fall downwardly. Furthermore, with this type of construction a large amount of air is forced through the filters and into the car, even though there is only a small pressure drop. At the same 45 time, the filters are of sufficient size to thoroughly clean the air. Accordingly, a thoroughly efficient and practical ventilator construction has been provided which effectively and efficiently overcomes many difficulties mentioned herein.

50 As many possible embodiments may be made of the above invention, and as many changes may be made in the embodiment above set forth, it is to be understood that all matter hereinabove set forth or shown in the accompanying drawings is to be interpreted as illustrative and not in a limiting sense.

I claim:

1. The combination with a railway car, of 55 means to deliver air to the interior of the car comprising, means forming an air inlet with an opening the mouth of which is in a plane extending in the direction of car movement, one edge of said opening being a leading edge when the car is moving in one direction, and means to deflect air into said air inlet comprising an elongated deflector having two edges extending along and spaced from said leading edge of the opening but being canted with respect to said leading edge with one end of said deflector spaced farther 60 from said leading edge than the other end, said deflector being streamlined in cross-section in the direction of car movement and one of its edges being a blunt edge positioned to break the wind when the car is moving in said one direction, said deflector being positioned with the

center of said blunt edge spaced a greater distance from the mouth of said opening than the other of said edges so that it deflects air into said opening when the car is moving in said one direction. 65

2. The combination with a railway car, of 70 means to deliver air to the interior of the car comprising, means forming an air inlet with an opening the mouth of which faces downwardly and is in a substantially horizontal plane extending in the direction of car movement, one edge of said opening being a leading edge when the car is moving in one direction, and means to deflect air in a generally upwardly direction into 75 said air inlet comprising an elongated deflector having two edges extending along and spaced from said leading edge of the opening but being canted with respect to said leading edge with one end of said deflector positioned lower than the other end and thus with said one end spaced 80 farther from said leading edge than said other end, said deflector being streamlined in cross-section in the direction of car movement and one of its edges being a blunt edge positioned to break the wind when the car is moving in said one direction. 85

3. The combination with a railway car of means 90 to deliver air to the interior of a car comprising, means forming an air inlet including a rim defining an opening the mouth of which faces generally downwardly and is in a plane which is substantially horizontal and extends in the direction of car movement, one edge of said opening being a leading edge when the car is moving in one direction, a filter means positioned over said opening and overlapping said rim, a pair of leaf springs 95 each mounted at its two ends and positioned to resiliently engage said filter, and means to deflect air through said filter and into said inlet comprising an elongated deflector which is tear-shaped in cross-section and which has a blunt 100 edge and a sharp edge extending along said leading edge of the opening, said blunt edge being positioned to break the wind when the car is moving in said one direction. 105

4. The combination with a railway car of means 110 to deliver air to the interior of the car comprising, means forming an air inlet in the outer wall of the car which inlet has its mouth for the entry of air in an outer surface extending in the direction of car movement, and means to deflect air toward said mouth comprising a pair of deflectors positioned along opposite edges of said mouth which edges are the leading and trailing edges when the car is moving, one of said deflectors being a leading deflector when the car is moving in one direction and the other of said deflectors being a leading deflector when the car is moving in the other direction, each of said deflectors being tear-shaped in cross-section to provide a blunt 115 edge which is the leading edge when the deflector is the leading deflector and a sharp edge which is the trailing edge, said blunt edge being spaced further from the plane of said outer surface than said sharp edge so that when said deflector is a leading deflector said blunt edges acts to cut the 120 air at the side of said outer surface. 125

5. The combination with a railway car of means 130 to deliver air to the interior of the car comprising, means forming an air inlet in the outer wall of the car which inlet has its mouth for the entry 135

- of air in an outer surface extending in the direction of car movement and said inlet having one edge which is the leading edge when the car is moving in one direction, and means to deflect air toward said mouth comprising a deflector positioned along said mouth, said deflector being tear-shaped in cross-section to provide a blunt leading edge and a sharp trailing edge when the car is moving in said one direction, said blunt edge having its center spaced further from the plane of said outer surface than said sharp edge with said sharp edge positioned substantially adjacent said mouth and with said blunt edge positioned substantially along said leading edge of said inlet, with the plane which extends through said blunt and sharp edges at an acute angle to the plane of said outer surface so that when the car moves in said one direction said blunt edge cuts the air at the side of said outer wall and air is deflected to said inlet.
6. The combination with a railway car of means to deliver air to the interior of the car comprising, means forming an air inlet on the outer surface of the car which inlet has its mouth in an outer surface extending in the direction of car movement, means to deflect air towards said mouth comprising, a pair of deflectors positioned along opposite edges of said mouth which edges are the leading and trailing edges when the car is moving, said deflectors being tear-shaped in cross-section in the direction of car movement and each of said deflectors having an axis at

right angles to the plane of said cross-section which axis is substantially along said mouth, said deflectors being positioned with the respective edges comprising the blunt portions of the tear-shaped cross-sections of the two deflectors extending away from each other and with the edge of each deflector comprising the sharp portion of the cross-section extending substantially toward said mouth.

7. The combination with a railway car of means to deliver air to the interior of the car comprising, means forming an air inlet on the outer surface of the car which inlet has a generally downwardly directed mouth in an outer substantially horizontal surface extending in the direction of car movement, means to deflect air towards said mouth comprising, a pair of deflectors positioned along opposite edges of said mouth which edges are the leading and trailing edges when the car is moving, said deflectors being tear-shaped in cross-section in the direction of car movement and each of said deflectors having an axis at right angles to the plane of said cross-section which axis is substantially along said mouth, said deflectors being positioned with the respective edges comprising the blunt portions of the tear-shaped cross-sections of the two deflectors extending away from each other and with the edge of each deflector comprising the sharp portion of the cross-section extending substantially toward said mouth.

LEO J. RICONDA.
